UNITED STATES PATENT OFFICE.

KENNETH E. BERRAY AND RICHARD W. STANLEY, OF LOCKPORT, NEW YORK, AS-
SIGNORS TO MERRITT MANUFACTURING CO., OF LOCKPORT, NEW YORK, A COR-
PORATION OF NEW YORK.

PROGRESSIVE PLATE DRYING MACHINE.

Application filed October 4, 1924. Serial No. 741,592.

This invention relates to drying machines and more particularly to machines adapted for the progressive drying of sheet material.

5 This invention has for its object generally to provide an improved construction and arrangement of parts which is efficient, economical and readily manufactured.

Specifically an object of the invention is 10 to provide a drying machine which is strong and rugged and adapted for heavy duty and for the progressive drying of large quantities of sheet material between heated platens with substantially a minimum expenditure 15 of energy.

Another object of the invention is functionally and structurally to improve the arrangement and co-ordination of the several 20 cooperating means which dry and automatically advance sheet material through drying machines, particularly through machines of the character set forth in copending application Serial No. 484,903, filed July 15, 1921.

25 Other objects of the invention will in part be obvious and will in part appear hereinafter.

The invention accordingly comprises the 30 features of construction, combinations of elements, and arrangement of parts, which will be exemplified in the construction hereinafter set forth and the scope of the application of which will be indicated in the claims.

35 For a fuller understanding of the nature and objects of the invention reference should be had to the following detailed description taken in connection with the accompanying drawing, in which:

40 Figure 1 shows in side elevation a drying machine adapted for the progressive drying of sheet material therein constructed in accordance with the invention;

45 Fig. 2 is a sectional view showing the plan of the base of an actuating means for the drying machine shown in Fig. 1;

50 Fig. 3 is a section taken on the line *a—a* of Fig. 1 and illustrates the mode of support for one of the group of platens in a stationary battery constructed in accordance with the invention;

55 Fig. 4 is a section taken on the line *b—b* of Fig. 1 and shows the mode of support for the group of platens cooperating with the group shown in Fig. 3;

Fig. 5 is a transverse section taken on the line *c—c* of Fig. 1 and shows the mode of support for a group of platens in a traveling battery constructed in accordance with the invention;

60 Fig. 6 is a transverse section taken on the line *d—d* of Fig. 1 and shows the mode of support for the group of platens cooperating with the group shown in Fig. 5;

65 Figs. 7 and 8 are fragmentary sectional views showing in enlarged views certain details in the platen supporting posts made in accordance with the invention;

70 Figs. 9, 10 and 11 are fragmentary sectional views showing details of the rocker construction employed in the invention, Figs. 9 and 11 being respectively sections taken on the lines *e—e* and *f—f* in Fig. 10;

75 Fig. 12 is a fragmentary view partly in section and partly in elevation taken on the line *g—g* of Fig. 2, looking in a direction of the arrows, and shows a detail in the gearing adapted to transmit motion to the traveling frame;

80 Fig. 13 is a similar view taken on the line *h—h* of Fig. 2 looking in the direction of the arrows and shows details in the mechanism for transmitting motion to the rocker;

85 Fig. 14 is an enlarged fragmentary view showing in elevation details in the manner of supporting the feed-bars on the end-posts in accordance with the invention;

90 Figs. 15 and 16 are fragmentary views showing respectively in plan and in side elevation further details in the construction of the feed-bars, while Fig. 17 is a cross section thereof.

95 Referring now to the drawings and more particularly to Figs. 1 to 6, 10 denotes generally the base for supporting the drying elements of the machine, the base being constructed of any suitable structural components for example, the four parallel longitudinally disposed I-beams shown at 11 which are held in proper relation by means of transversely disposed channel bars 12. 100 The base 10 supports on each side a plurality of rockers 13. As shown there are three rockers 13 on each side of the machine which are distributed along the outside I-beams 11. Transverse shafts 15 rigidly connects opposite rockers on each side of the machine providing thereby three pairs; these shafts as shown in Fig. 2, are con-

veniently journaled in bearings 16 mounted on the inside I-beams. A simultaneous rocking motion is communicated to the six rockers in a manner more fully explained hereinafter, whereby they impart a reciprocating motion to the upper and lower portions of the platen supporting frames which are generally designated 18 and 19.

The frame 18, as shown in Fig. 1, comprises lower and upper girders 20 and 21, the former of which are shown as secured to each of the platen supporting posts, 22, which are pivoted as shown in Fig. 3, at 24 to one side of the rockers 13 in order to be reciprocated thereby. Parallel to the platen supporting posts 22 is a second set of platen supporting posts 23 which, as shown in Fig. 4, are likewise pivoted to the rockers 13 at 25 but on diametrically opposite sides of the center. The posts 22 and 23 accordingly are simultaneously reciprocated by the rockers 13, but are always in opposite phases of the reciprocation imparted, that is, when the posts 21 are in the upward moving portion of the cycle then the posts 23 are in the downward moving portion and vice versa. The platen supporting posts 23 are not connected to the lower girders 20, but as shown clearly in Fig. 4 slide loosely therebetween. The upper girders 21 are however rigidly secured to the each of these platen posts 23. Similarly the platen supporting posts 22, which are secured to the lower girders 20 are arranged to operate slidably between the upper girders 21 as indicated clearly in Fig. 3. The frame 18 is thus seen to comprise upper and lower girders 20 and 21 which respectively carry the platen supporting posts 22 and 23; and are moved toward and from each other with each reciprocation of the platen supporting posts. Groups of platens are supported on these posts, their positions being shown mainly by dotted lines in Fig. 1; these groups will be hereinafter referred to as "batteries" and designated generally by the numeral 26.

In order to aid in supporting the platens of each battery there is disposed parallel to each platen supporting post 22 and 23 an auxiliary platen supporting post designated respectively 22' and 23'. The posts 22' are not directly connected to the rocker but are secured to the lower girders 20 and as shown in the drawing are preferably disposed to the right of the posts 23. The posts 23' on the other hand, are likewise not directly connected to the rocker, but are secured to the girders 21 to which the posts 23' are secured; the posts 23' being preferably disposed as indicated in Fig. 1 to the left of the posts 22. It is thus seen that there is provided a group of four parallel posts, each alternate one being secured to the same girder and having the same mo-

tion. As there are three rockers on each side of the machine, there are three groups of platen posts directly reciprocated by the rockers. The frame 18, however, is adapted to provide reciprocation for platen supporting posts arranged at any of its intermediate points. Accordingly midway between the left hand and middle groups is another group of four platens supporting posts, namely, those secured to the girders 20 and 21 designated respectively 22'' and 23''. A similar group of four posts is shown between the middle and right hand groups of directly rocker-actuated supporting posts.

The frame 18, as illustrated, thus supports five batteries 26 in spaced interleaved relation, and is hereinafter referred to as the "stationary frame"; the batteries which it supports, being referred to as "stationary batteries."

The frame indicated generally at 19 is designed to be movable with respect to the stationary frame 18 and is hereinafter referred to as the "traveling" frame. The traveling frame comprises lower and upper girders 30 and 31 disposed parallel respectively to but above girders 20 and 21 and supported therefrom preferably by anti-friction means, for example by roller bearings, as shown at 27.

The bearing construction illustrated, as more clearly shown in Fig. 5, comprises a plurality of relatively narrow rollers 28 of relatively large diameter pivoted between the lower girders 20 and between the upper girders 31, which ride or bear upon bearing plates 29 spanning respectively the pairs of girders at 30 and 21 on each side of the machine.

The traveling frame 19 is arranged to have a limited to and fro movement and to support batteries between the stationary batteries which partake of the motion of the traveling frame. Such batteries are here designated "traveling batteries." To support the traveling batteries, the lower girders 30 of this frame have pairs of parallel spaced platen supporting posts designated 32 and 32' which are disposed in alternate relation with a pair of posts 33 and 33' secured to the upper girders 21 thereby providing groups of four posts which have alternately opposite reciprocating movements similar to the group of posts 22, 22', 23 and 23'. These additional group of posts 33 and 33' of course travel with the traveling frame and are disposed along the girders at points adapted to support the traveling batteries between the stationary batteries with the proper clearances for the desired travel. The traveling frame as shown thus supports batteries from the frame 18.

The batteries 26 which are carried by each group of platen supporting posts comprise platen units having flat upper and

lower surfaces adapted to apply pressure. These platen units as indicated more clearly in Figs. 7 and 8 are in the form of hollow castings 35, which preferably have lugs at 5 their ends as shown at 36 and 36' adapted to bear upon transverse bars 37, secured to the platen supporting posts in any suitable manner, for example, by means of the bolt 38 shown as frictionally and adjustably 10 supported by means of nuts 38' in the slot 39 formed in the end wall of the platen supporting posts. Pipe connections, herein-after more fully described, are adapted to supply a heating medium thereto, such for 15 example, as live steam under pressure.

The traveling frame 19 as shown has overhanging ends which are completed by a pair of sliding rods 40 and 41 that are secured respectively to the girders 30 and 31 as more 20 clearly shown in Fig. 14. The upper end of post 40 as shown in Fig. 14 is provided with guiding prongs 42 which extend over and loosely engage with the sides of the rod 41. The lower end of the rod 41 is also provided with similar guiding prongs 43. It is thus seen that these rods are adapted for reciprocation and move one upon the other with the up and down movements of the girders 30 and 31. These rods are provided 25 with projections 44 and 45 disposed respectively on the rods 40 and 41 so that each rod supports alternate ones of the feed bars 46 which are disposed in superposed spaced relation as clearly indicated in Fig. 14. These feed bars have a pair of lugs 47 which are adapted to embrace the rods 40 and 41 and bear upon the projections 44 or 45 as the case may be. At one end as shown in Fig. 30 15, the feed bar has a removable lug 47' in order that such lug may be taken off to facilitate the insertion or removal of a bar from its place on the reciprocating rods. These feed bars preferably are made U-shaped in cross section, but are turned so as 35 to lie on a side as shown in Fig. 17. The closed outer face of each feed bar has its upper and lower edges bevelled as indicated at 48 and when placed in position has these bevelled parts so arranged as to provide a converging opening for the reception of the sheet material to be pressed and dried. By this construction it is seen that the feed bars on the ends of the traveling frame 19 partake of substantially the same motion as the 40 traveling batteries with which their openings are aligned.

By reciprocating the lower and upper girders 20 and 21 which carry girders 30 and 31 it is seen that alternate platens in each group or battery are moved in unison toward or from each of the adjacent platens in the battery. The platens of each battery are adapted to approach each other until they grip the sheet material which they 45 press between their flat surfaces but in case

the motion of the platen supporting posts is not such as to stop when two platen surfaces are brought to bear oppositely against the sheet material, it is seen that, since the castings 35 are loosely supported 50 by the platen supporting posts, the lowermost platen is free to lift the then superincumbent platen from its support and bear such weight until the movement of the platen supporting post again picks up the 55 platen. The rockers 13 which thus effect this reciprocation are here simultaneously oscillated in a positive manner; the rockers themselves being preferably of a rugged construction and substantially frictionless in 60 their operation.

The details of the rocker construction are shown in Figs. 9, 10 and 11, where 50 denotes a supporting chair which is adapted to be secured on the I-beams 11 of the base 10. 85 The chair 50 supports the oscillating segment 51 having roller bearings 52 distributed properly over the bearing surfaces of the chair 50 and the oscillating member 51 which surfaces preferably are reinforced 90 by means of thin sleeves of properly hardened bearing metal 53, the latter being secured by means of screws 54. The rollers 52 are themselves shown as mounted in arcuate frames 55 which are disposed at the 95 ends of the rollers and within properly formed grooves at the sides of the chair 50. These frames 55 have a limited end-wise movement and insure that the rollers are constantly in alignment and not likely 100 to add to the friction within the chair on account of their getting out of alignment. These frames also are preferably constructed so as to assist in the distribution of lubricant to the bearing surfaces in the chair; 105 for example by providing properly formed capillary grooves in the frames.

The oscillating segment 51 has a hub 56 into which an end of the shaft 15 is secured in any suitable manner, for example, by means of the set screws 57. Depending from the hub 56 is a heavy integral rocker arm 58 which is adapted to receive motion from a pair of links 59 in order to rock it. The links 59 are secured to the end of the 110 arm 58 by means of the pin 60 which passes through an opening in the lower end of the rocker arm, the opening being lined with a sleeve 61 so as to provide a proper bearing and eliminate any substantial lost motion. 115 This sleeve however is provided with openings 62 communicating with passages 63 adapted to supply a suitable lubricant from the well indicated at 64. The oscillating segment 51 has a pair of crank pins 65 which are preferably secured to the outside vertical face at diametrically opposite points disposed at equal distances from the center. These crank-pins serve as pivots to which 120 the directly actuated platen supporting 125

posts 22 and 23 are operatively connected in order to be reciprocated. The connections to these crank-pins are protected and kept in place by means of the removably secured plate 66.

The chairs 50, as constructed, are seen each to form the lower member of what is a bearing block for the oscillating segment 51. The bearing block thus provided however is not formed with a completely arched-over upper member, but has what in effect is an upper member with the central portion cut away so as to provide ready access to the parts in order to repair or to lubricate the parts. The chairs 50 thus have on each of their upwardly projecting right and left arms, a shoulder piece 50', which is individually removable therefrom and gives the chair when complete a somewhat crescent-shaped outline. These pieces prevent the accidental or unauthorized displacement of the oscillating segment 51 from its chair.

The pair of links 59 as shown in Fig. 2 are adapted to connect all three of the rockers on a side of a machine so that they may be rocked simultaneously. These links 59 are shown also in Fig. 13 and carry, at a point intermediate their connections to the rocker arms 58, a pair of spaced rollers 67 which serve as anti-friction rollers for receiving motion to reciprocate the links from the cam 68 that is shown in broken lines as mounted on a shaft 69. Two such shafts are shown in Fig. 2, one on the left hand side of the plan view and one on the right hand side. These shafts extend clear across the machine and are driven synchronously by means of gearing shown at 70 which in turn is driven by reduction gearing shown at 71, the latter being driven from the jack shaft 72 actuated in any suitable manner, for example, by means of the electric motor 73, having driving connections with the jack shaft 72 indicated at 74. Each pair of rollers 67 and their respective cams are preferably protected as shown in Figs. 2 and 13 by means of a housing 75 which is carried on the links 59, the cams in each case being so arranged on shafts 69 as to have the same phase when actuated.

The traveling frame 19 is arranged to travel in a properly timed relation with the reciprocations imparted to the upper and lower girders of both frames. By means of this timed relation the traveling batteries move forward, advancing the sheet material which they grip into the aligned openings of the adjacent stationary batteries which openings in this phase of the movement are open. Correspondingly, the sheet material which is being held securely between platen surfaces in the stationary batteries must extend into aligned openings of the adjacent traveling battery which are then open. This sequence of operations is the same as that set

forth in the co-pending application above identified.

In the arrangement here shown this timed relation in the sequence of the movement of the traveling frame 19 with respect to the reciprocation of the platens is secured by means of a cam which is additional to the cams 68, but is actuated by the shaft 69; all the cams being properly angularly disposed on the shaft so as to provide for the desired movements each at the proper time. The cam, for thus actuating the traveling frame, is shown in broken lines at 77 in Fig. 12 and mounted on the left hand shaft 69 (see Fig. 2,) which turns in a bearing block 78 sliding in ways 79 in the side of the housing 80. This housing carries within it a pair of rollers 81 which contact substantially at diametrically opposite points of the cam 77. The housing 80 thus formed serves as a pitman 82 which is adapted to receive the reciprocating motion imparted by the cam 77 and transmit it to a rocking link 83 which is pivoted at 84 to one of the transverse shafts 15. The rocking link 83 carries an adjustable sliding block 85 in a slot 86 which is disposed longitudinally of the link 83 and made to pass in transit as close as practical to the shaft 15. To the sliding block is pivoted, as indicated at 87, a link or rod 88 which is connected at 89 to a transverse bar 90 of the traveling frame. As the rocking link 83 is rocked, it is seen that a reciprocating movement is transmitted by the rod 88 and causes the frame 19 to travel. The amplitude of this motion is varied by adjusting the block 85 up or down in the slot 86. This adjustment is effected by any convenient means, for example, by means of the screws 91 which are disposed in the slot 86, and arranged to move the block 85 longitudinally therein. The screw 91 is actuated by means of a train of gears 92, which is moved by means of a hand-wheel 93. This hand-wheel as will be seen, is disposed at the end of a transverse shaft 94 which is journaled in a suitable projection 95 formed on a part of link 83 which has a relatively small amplitude of motion. As there is a rocking link 83 on each side of the machine, these links are arranged to be operated in synchronism; the shaft 94 is accordingly journaled in both links and serves as a means for simultaneously adjusting the amplitude of the reciprocation communicated to the traveling frame 19.

As the advance of frame 19 preferably takes place during the intervals between successive reciprocations of the platens, the cam 77 in consequence is given an angular displacement on the shafts 69 with respect to the cams 68 of substantially 90 degrees. By providing the swinging link 83 with an adjustable block 85, it is seen that there is thus provided means for varying the amplitude 100

of the reciprocating motion imparted to frame 19 without the use of a lost-motion connection between the cam 77 and the frame 19.

5 By varying the travel of the frame 19 it is seen that the rate of the feed of sheet material passing between the platens is controlled.

In the construction here illustrated, both 10 the cams 68 and 77 are operatively disposed between a pair of rollers to which their motion is imparted. The cams are preferably so shaped as to bear continually upon the rollers during the complete cycle of operations 15 imparted in a revolution of shaft 69. Consequently there is no lost motion at any point to be taken up, and the strains incident to the taking up of lost motion are thus avoided and a longer life had for the machine and its operating parts, while the rollers themselves serve as anti-friction members for transmitting the motion of the cams substantially frictionlessly. It will be observed that, by the use of cams as here provided, the motion 20 of the reciprocating parts need not necessarily be a simple harmonic motion, but one compounded of suitable harmonic components. Also by providing the cams with housings, they are protected from knocks and dirt which frequently add to the strains incident to cam-propelled apparatus. Such a cam casing is also preferably made to serve as a reservoir for oil or other lubricant. Consequently the rollers and cam, 25 when bathed with lubricant from such reservoir become well oiled and thereby further avoid the strains incident to wear. Portions of the driving train in this machine are also shown as having suitable housings which 30 protect them from dirt and may likewise serve to supply lubricant to the train.

The heating medium, which is preferably dry steam, is supplied to the stationary and traveling batteries from respective separate headers. The supply-header for the stationary batteries is designated 100 while that for the traveling batteries is designated 101; both are clearly shown in Fig. 1. From the header 100 at proper intervals there are led 40 flexible pipe connections 102 which pass down at the side of the frame adjacent to the supporting posts and through suitable openings in the posts, indicated at 103, into the steam inlets 104 of the platens. At the opposite 45 ends of the platens there are exits 105 as shown in Figs. 5 and 7 which are preferably disposed near the bottoms of the platens to drain off as far as practical all the water of condensation. The pipe connections for 50 draining off the water of condensation from the platens of a stationary battery are indicated at 106. These connections are also flexible and lead to a drain-header 107 shown on the left in Fig. 5 supported by a channel 55 bar 12 of the base. The header 107 in turn

has a pipe connection 108 connecting with a trap 109 shown in Fig. 1.

The header 101 is carried on the traveling frame 19 by means of the bracket 110 and is supplied with live steam through the articulated connection 111. From the header 101 lead other flexible pipe connections 112 which pass respectively to the platens of the traveling batteries through openings 113 in the traveling supporting posts 32, 32', 33 and 33'. From the opposite ends of the platens of the traveling batteries lead the flexible drain connections 116. These connections communicate with the drain header 117 shown also as carried by the traveling frame 80 by means of the bracket 118. The traveling drain-header has an articulated pipe connection 119 shown in Fig. 1 which connects with the trap 109. The supply connections preferably have valves as shown so that 85 they may be controlled. By means of this arrangement of piping it is seen that a free or regulated flow of the heating medium to each platen and the proper drainage of the condensate therefrom are secured substantially as desired.

Operation.

The sheet material to be pressed and dried, for example wood-veneer, is preferably fed 95 simultaneously at both ends of the machine since each end is designed both to receive and to discharge the sheet material which is to be treated. The material is fed in any convenient manner, for example, by hand or by traveling conveyors which are suitably disposed adjacent the ends of the traveling frame, but are not here shown in the interests of clearness.

Let it be assumed that the machine is 105 running, that the cams 68 and 77 turn in a clockwise direction and that, in the position shown in Figs. 12 and 13, they are in the midst of what is here termed the first quarter of a cycle. In this position it will be 110 seen that the cam 77 has pushed the pitman 82 and the rocking link 83 to the extreme right-hand position. The traveling frame 19 will accordingly be in its extreme right-hand position. In this portion of the cycle, 115 however, the cam 68 is in an intermediate position, the rocker arm 58 being shown vertically downward. The platens and the feed bars, for this position of the rocker arm, will all be in the midst of an opening and 120 closing movement. It is seen from an inspection of Fig. 13 that the supporting posts 22 will move upwardly and that the posts 23 will move downwardly as this quarter of 125 a cycle is being completed. This will cause the two lowermost platens in the right-hand stationary battery shown in Fig. 1 to be closed at the end of the first quarter of the cycle.

The movements of the feed bars (also that 130

of the traveling platens) and that of the corresponding stationary platens will, of course, be in diametrically opposite phases, that is, the two lowermost feed bars on the right-hand end of the traveling frame will be opening while that of the lowermost two platens in the stationary battery will be closing, etc. The sheet material at the right end will accordingly be fed into the second and fourth 10 openings from the bottom of the feed bars, while that at the left-hand end is fed into the first and third openings from the bottom.

When the first quarter of a cycle is completed, the rocker arm 58 will have been 15 rocked into its extreme right-hand position, thereby bringing supporting post 22 to its most elevated position, while supporting post 23 is depressed to its lowermost position. The second and fourth openings between the feed-bars of the right-hand end are thereby closed, so as to grip the sheet material which has been fed thereinto since the frame 19 is just about to begin its travel toward the left. All the traveling batteries 20 have, of course, partaken of the same motion as the feed bars so that their aligned second and fourth openings from the bottom are likewise closed and grip any sheet material which may have already reached them.

30 The second quarter of the cycle begins when cam 68 has reached its extreme left-hand position. Cam 77 by this time has also turned sufficiently downwardly to be imparting motion to the pitman 82 so as to swing 35 the link 83 toward the left. The frame 19 accordingly travels steadily toward the left during the second quarter of the cycle; the cam 68, during this quarter, rolling substantially frictionlessly without imparting motion 40 of translation, against the left-hand rollers 67 carried by the links 59. The sheet material fed from the right is thus held gripped between the platens of the traveling batteries and between the feed bars and is 45 thereby drawn toward the left and made to advance in the open spaces of the stationary batteries as the second quarter transpires; such quarter terminates when the traveling frame 19 has reached its extreme left-hand 50 position.

During the next or third quarter of the cycle the cam 68 will have turned clockwise into a position displace 180° from that shown in Fig. 13. In this position the links 55 59 will have come back to the full-line position and the rockers 13 will again have assumed the intermediate position; the cam 77 shown in Fig. 12 will also have been angularly displaced 180° from the position shown 60 in dotted lines, so that the pitman 82 will thus have reached its extreme left-hand position and the rocking link 83 rocked to its extreme left-hand position.

In consequence the link 88 will have 65 moved the traveling frame 19 to its extreme

left-hand position. The cams 68 and 77 are so designed that the frame 19 will have reached its position prior to any movement imparted to the rocker arm 58.

As a result, the sheet material which is gripped in the second and fourth spaces from the bottom of the traveling batteries and of the feed bars will have been given a full displacement equal to the distance traversed by the frame 19 and then be released 75 while that in the alternate spaces of the traveling batteries will then be gripped, preparatory to being displaced toward the right.

During the fourth quarter of the cycle 80 the cams 68 and 77 will have been moved to positions displaced by 270° clockwise from that shown in Figs. 12 and 13. The traveling frame will have been moved during this quarter of the cycle from the extreme left-hand position to the extreme right-hand position. During this final quarter the cam 68 rolls substantially frictionlessly on the right-hand rollers 67 on the links 59, as in the second quarter, thereby maintaining the 85 first and third spaces from the bottom of the traveling batteries and of the feed bars in gripping engagement with the sheet material fed from the left, while the cam 77 rocks link 83 to effect translation of frame 19 to the right. When this translation is completed the sheet material which was gripped by the stationary batteries and not moved during the first half cycle has now 90 been moved toward the right a distance corresponding to the full displacement of the traveling frame 19, while that moved during the first half cycle remains stationary, being gripped in the now closed second and fourth spaces from the bottom of the stationary batteries. The rate of travel of the sheet material through the drying machine is 95 varied at will according to the result desired in either of two ways; first, by varying the speed of the motor 73 which also varies 100 the time the platens remain in contact with the sheet material during a cycle, or second, by varying the amplitude of the travel of the frame 19, by varying the position of block 85 in link 83 as indicated above. 105

The drying effect of the platens on the sheet material may also be regulated independently. The regulation of this effect is accomplished by regulating the heating, and consequently the supply of the heating medium to the headers 100 and 101, which is 110 preferably accomplished by manipulating the valves in the piping above described.

It is thus seen that the drying machine here provided operates to discharge properly pressed and dried sheet material intermittently but progressively from the machine at each end, the material having advanced through the machine in relatively 115 opposite directions. It is seen also that the 120

supporting posts, attached to the relatively movable frames 18 and 19 and arranged in groups of fours, provide for supporting each platen at four distinct points. This quadrilateral support of the platens insures a rigid three-point support for the platens even though the frames become somewhat permanently strained and do not provide even support at all four points; the platens by this arrangement consequently keep at all times closely to their original planes. In the frame construction here employed, it may be noted however that the lower and upper members of the frame 18, namely, the girders 20 and 21, are illustrated as preferably made of relatively wide channel bars in order to give the frame stiffness in a vertical direction and thereby avoid as far as practical the risk of permanent strains. In this construction, it is further seen that these members support, though movably and in a substantially frictionless manner on account of this interposition of rollers 28, the lower and upper girders 30, and 31 of the frame 19, so that the frame 18, in consequence, carries the total weight of all the batteries, both traveling and stationary; the traveling batteries being preferably disposed directly over the rollers 28 carried by the lower girders 20 of the frame 18; the rollers themselves being preferably disposed so as to support the load at points of substantially maximum stresses.

As the upper and lower girders 20 and 21 are directly connected to and hence supported by the rockers 13, it is seen that these rockers in turn support the entire weight of the batteries. As indicated there are three rockers on a side, so that the base 10 has six rockers on which the entire weight of the batteries is applied in the form of concentrated loads at those points. It is for this reason that the bearings for the rockers 13 are made with anti-friction devices and of massive construction so as to provide ample bearing surface of a rigid character for carrying the total load without undue consumption of operating energy.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described our invention, what we claim as new and desire to secure by Letters Patent, is:

1. In a drying machine, in combination, a stationary frame and a traveling frame each having members relatively movable toward and from the other, spaced interleaved platens provided with quadrilateral supports carried by said movable members, and means

for reciprocating said movable members and simultaneously moving said traveling frame in cyclic relation with said reciprocation.

2. In a drying machine, in combination, a stationary frame and a traveling frame each having members movable toward and from the other, supporting posts carried by said movable members and arranged in relatively movable groups of fours, spaced interleaved platens supported in quadrilateral fashion by said supporting posts at each end of said platens, and means for reciprocating said movable members and simultaneously moving said traveling frame in cyclic relation with the reciprocations.

3. In a drying machine, in combination, a stationary frame and a traveling frame each having upper and lower members movable relatively toward and from the other, supporting posts carried by said upper and lower members and arranged in relatively movable groups of fours, spaced interleaved platens arranged in groups and supported by said post, alternate ones being supported by the same pair in each group of four, and means for reciprocating said members and simultaneously moving said traveling frame in cyclic relation with the reciprocations.

4. In a drying machine, in combination, a stationary frame having vertical stiffened upper and lower horizontal members, a traveling frame having upper and lower horizontal members carried by said stiffened members, the upper and lower members of each frame being movable toward and from the other, relatively movable supporting posts carried by the upper and lower members of each of said frames and arranged in groups of fours, spaced interleaved platens arranged in groups and supported by said posts, alternate ones being supported by the same pair in each group of four, and means for reciprocating said members and simultaneously moving said traveling frame in cyclic relation with the reciprocations.

5. In a drying machine, in combination, a stationary frame having vertically stiffened upper and lower horizontal members, a traveling frame having upper and lower horizontal members carried in rolling contact with said stiffening members, the upper and lower members of each frame being movable from and toward the other, supporting posts carried by each of said upper and lower members and arranged in groups of fours, batteries of spaced interleaved platens supported by each group of four, the batteries carried by said traveling frame being disposed intermediately between the batteries on said stationary frame, and means for reciprocating said members and simultaneously moving said traveling frame in cyclic relation with said reciprocations.

6. In a drying machine, in combination, a stationary frame having vertically stiff-

ened upper and lower horizontal members, a traveling frame having upper and lower horizontal members and provided with roller-bearing support on said stiffened members, the upper and lower members of each frame being movable toward and from the other, pairs of supporting posts carried on each of said upper and lower members, a pair on each of said upper and lower members being associated in groups of fours, a group of spaced interleaved platens comprising a battery supported by each said group of four, alternate platens of a battery being supported by the same pair in a group of four, and means for reciprocating said members and simultaneously moving said traveling frame in cyclic relation with said reciprocations.

7. In a drying machine, in combination, a stationary frame having vertically stiffened upper and lower horizontal members, a traveling frame having upper and lower horizontal members provided with roller-bearing support on said stiffened members, the upper and lower members of each frame being movable toward and from the other, pairs of supporting posts carried on each of said upper and lower members, a pair on each of said upper and lower members being associated together in groups of fours, said groups being disposed directly over and under the roller-bearing support for the traveling frame, a battery of spaced interleaved platens supported by each of said

35 groups, alternate platens of a battery being supported by the same pair in a group, and means for reciprocating said members and simultaneously moving said traveling frame in a cyclic relation with said reciprocations.

40 8. In a drying machine, in combination, relatively movable platen supporting frames, each having upper and lower members adapted to be moved toward and from the other, the members of one frame being vertically stiffened and adapted to support the members of the other, means carried by said members for successively gripping and advancing sheet material in said drying machine, and means for moving said members and frames intermittently in recurrent cycles.

45 9. In a drying machine, in combination, relatively movable frames, each having upper and lower members adapted to be reciprocated toward and from the other, the members of one frame being vertically stiffened and provided with roller-bearing support for the members of the other frame, means for successively gripping and advancing sheet material supported by said members as concentrated loads at the bearing point, and means for moving said frames relatively and reciprocating said members intermittently in recurrent cycles.

50 10. In a drying machine, in combination,

relatively movable frames each having upper and lower members adapted to be reciprocated toward and from the other, the members of one frame being vertically stiffened and provided with roller-bearing support for the members of the other frame, batteries of spaced interleaved platens mounted on said frame at points adjacent the roller-bearing support, and means for moving said frames relatively and reciprocating said members intermittently in recurrent cycles. 75

11. In a drying machine, in combination, a base, relatively movable distensible frames on said base, one of which has overhung ends, relatively movable feed bars carried by said ends and arranged to grip and advance sheet material to feed it into the machine, and means mounted on said base for actuating said frames and said feed bars 80 intermittently in recurrent cycles. 85

12. In a drying machine, in combination, a base, relatively movable distensible frames on said base, one of which has overhung ends, means for gripping and advancing 90 sheet material in said drying machine including relatively movable feed bars carried at said ends, and means mounted on said base for actuating said gripping and advancing means intermittently in recurrent 95 cycles.

13. In a drying machine, in combination, a base, a stationary frame mounted on said base and having relatively reciprocating supporting posts, a traveling frame carried 100 by said stationary frame and having associated reciprocating supporting posts, batteries of spaced interleaved platens carried by said supporting posts having their openings aligned for receiving sheet material, feed bars carried at the ends of said traveling frame arranged to be relatively reciprocated and to have their openings aligned with the spaces in said batteries, and means for reciprocating and advancing the movable portions of said frames intermittently 105 in recurrent cycles. 110

14. In a drying machine, in combination, a base, relatively movable distensible frames, means mounted thereon for successively gripping and advancing sheet material in said machine, one of said frames being provided at its ends with superposed sliding rods, and means for imparting motion to said movable frames to actuate said gripping and advancing means intermittently in recurrent cycles. 115

15. In a drying machine, in combination, a base, relatively movable distensible frames supported by said base, one of said frames being provided with overhung ends, superposed sliding rods arranged to complete said ends, feeding means mounted on said sliding rods adapted to grip sheet material alternately on opposite sides, and means for 120 125 130

the successive heating and pressing of sheet material carried by said frames, and means for moving said frames to actuate said feeding and heating means intermittently in recurrent cycles.

16. In a drying machine, in combination, means for gripping and advancing sheet material in said machine, and means for actuating said gripping and advancing means, intermittently in recurrent cycles, said means including synchronously driven cams having relative phase displacement and links connected to said gripping and advancing means for transmitting thereto the motion of said cams, said links being provided with motion-receiving elements arranged to be in constant rolling contact with said cams.

17. In a drying machine, in combination, relatively movable frames provided with reciprocating platens arranged successively to grip and advance sheet material in said machine, and means for actuating said platens intermittently in recurrent cycles, said means including synchronously driven cams and motion-transmitting links actuated thereby, said links having rollers in constant rolling contact with said cams and arranged to transmit the motion of said cams to move said platens intermittently in recurrent cycles.

18. In a drying machine, in combination, relatively movable frames having upper and lower members adapted to be reciprocated toward and from each other, a base, rockers on said base having operative connections to reciprocate said members, links connected to said rockers to insure synchronous movement thereof, a pitman connected to impart relative movement to said frames, power driven cams journaled on said base and having relative phase displacement, and means having constant rolling contact with said cams disposed respectively on said links and pitman to impart movements to said frame and members intermittently in recurrent cycles.

19. In a drying machine, in combination, relatively movable frames having upper and lower members adapted to be reciprocated toward and from each other, a base, rockers on said base having operative connections to reciprocate said members, links connected to said rockers to insure synchronous movement thereof, a pitman connected to impart relative movement to said frames, power driven cams journaled on said base and having relative phase displacement, and housings each provided interiorly with rollers adapted to be in constant rolling contact with said cams disposed respectively on said links and pitman.

20. In a drying machine, in combination, relatively movable frames having upper and lower members adapted to be reciprocated

toward and from each other, a base, rockers on said base having operative connections to reciprocate said members, links connected to said rockers to insure synchronous movement thereof, a pitman connected to impart relative movement to said frames, power driven cams journaled in said base and having relative phase displacement, and casings each adapted to contain lubricant and provided with rollers arranged to be in constant rolling contact with said cams, disposed respectively on said links and pitman to receive the motion imparted by said cams and actuate said frames and members intermittently in recurrent cycles.

21. In a drying machine, in combination, a base, relatively movable frames, each having upper and lower members adapted to be reciprocated, spaced interleaved platens disposed in groups and supported by said members, rockers supported by said base and having operative connections with said members to reciprocate the same, said rockers having relatively large bearing surface, means for supplying lubricant to said surfaces, and means for swinging said rockers in synchronism and for imparting motion to said relatively movable frames intermittently.

22. In a drying machine, in combination, a base, reciprocable spaced drying elements, rockers arranged to reciprocate said elements, and bearing members for said rockers supported by said base, said members comprising substantially semi-circular chairs and anti-friction devices on which said rockers bear.

23. In a drying machine, in combination, a base, reciprocable spaced drying elements, rockers arranged to reciprocate said elements, and bearing members for said rockers supported by said base, said members comprising substantially semi-circular chairs providing a cylindrical bearing surface and anti-friction rollers distributed over said surface and arranged to support said rockers thereon.

24. In a drying machine, in combination, a base, reciprocable spaced drying elements, rockers arranged to reciprocate said elements, and bearing members for said rockers supported by said base, said members comprising substantially semi-circular chairs having a cylindrical bearing surface, anti-friction rollers distributed over said surface, and rings arranged to hold said rollers in alignment, said rollers being adapted to support the weight of said rockers.

25. In a drying machine, in combination, a base, reciprocable spaced drying elements, rockers arranged to reciprocate said elements, and bearing members for said rockers supported by said base, said members comprising substantially semi-circular chairs provided with arms, anti-friction devices on

which said rockers bear, and individually removable shoulder pieces on the arms of said chairs and arranged to hold said rockers in place.

5 26. In a drying machine, in combination, a platen supporting frame, a second platen supporting frame supported for movement relatively to said first mentioned frame, a plurality of batteries of spaced interleaved platens arranged side by side and each including a plurality of drying platens, a plurality of supporting posts for said platens connected to said platen supporting frames whereby the platens connected to the movable frame are movable therewith and relatively to the adjacent platen, and spaced supporting lugs at opposite ends of each of said platens supported respectively by spaced platen posts.

10 27. In a drying machine, in combination, a platen supporting frame, a second platen supporting frame supported for movement relatively to said first mentioned frame, a plurality of batteries of spaced interleaved platens arranged side by side, a plurality of supporting posts for said platens connected to said platen supporting frames whereby the platens connected to the movable frame are movable therewith and relatively to the adjacent platen, spaced supporting lugs at opposite ends of each of said platens supported respectively by spaced platen posts, and bearings for said platen supporting frames disposed directly beneath said terminal batteries.

15 28. In a drying machine, in combination, a platen supporting frame, a second platen supporting frame supported for movement relatively to said first mentioned frame, a plurality of batteries arranged side by side and each including a plurality of drying platens, a plurality of supporting posts for said platen connected to said platen supporting frames whereby the platens connected to the movable frame are movable therewith and relatively to the adjacent platen, spaced supporting lugs at opposite ends of each of said platens supported respectively by spaced platen posts, the terminal batteries of said machine being supported by said first mentioned platen supporting frame, bearings for said platen supporting frames disposed directly beneath said terminal batteries, and feed bars carried by said second mentioned platen supporting frame and operating therewith to feed the material into the machine.

20 29. In a drying machine, in combination, a platen supporting frame having upper and lower longitudinal members, a second platen supporting frame having upper and lower longitudinal members arranged in the plane of said first mentioned members and supported for longitudinal movement thereon, platen supporting posts carried by said mem-

bers, platens carried by said posts, a supporting base for said frames disposed below the plane of said members, and rocker bearings supported on said base having supporting connections with said first mentioned frame.

25 30. In a drying machine, in combination, a platen supporting frame having upper and lower longitudinal members, a second platen supporting frame having upper and lower longitudinal members arranged in the plane of said first mentioned members and supported for longitudinal movement thereon, platen supporting posts carried by said members, platens carried by said posts, each being supported at each end at spaced points by a plurality of said posts, a supporting base for said frames disposed below the planes of said members, and rocker bearings supported on said base having supporting connections with said first mentioned frame.

35 31. In a drying machine, in combination, a platen supporting frame having upper and lower longitudinal members, a second platen supporting frame having upper and lower longitudinal members arranged in the plane of said first mentioned members and supported for longitudinal movement thereon, platen supporting posts carried by said members, platens carried by said posts, said platens being grouped as a plurality of relatively movable batteries, a supporting base for said frames disposed below the planes of said members at either side of said machine, and rocker bearings supported on said base beneath the terminal batteries, and having supporting connections with said first mentioned platen supporting frame.

40 32. In a drying machine, in combination, a platen supporting frame having upper and lower longitudinal members, a second platen supporting frame having upper and lower longitudinal members arranged in the plane of said first mentioned members and supported for longitudinal movement thereon, platen supporting posts carried by said members, platens carried by said posts, each being supported at each end at spaced points by a plurality of said posts, said platens being grouped as a plurality of relatively movable batteries, a supporting base for said frames arranged in the planes of said members at either side of said machine, and rocker bearings supported on said base beneath the terminal batteries, and having supporting connections with said first mentioned supporting frame.

45 33. In a drying machine, in combination, a platen supporting frame having upper and lower longitudinal members, a second platen supporting frame having upper and lower longitudinal members arranged in the planes of said first mentioned members and supported for longitudinal movement thereon,

platens supporting posts carried by said members, platens carried by said posts, said platens being grouped as a plurality of relatively movable batteries, a supporting base for 5 said frames disposed below the planes of said members at either side of said machine, rocker bearings supported on said base beneath terminal batteries, having supporting connections with said first mentioned platen 10 supporting frame, and feed bars carried by said second mentioned platen supporting frame and operating therewith to feed material into the apparatus.

34. In a drying machine, in combination, 15 a platen supporting frame having horizontally spaced upper and lower longitudinal members, a second platen supporting frame having horizontally spaced upper and lower longitudinal members arranged respectively 20 in the planes of said first mentioned members and supported for longitudinal movement thereon, platen supporting posts carried by said members, platens carried by said posts, a supporting base for said frames including 25 beams disposed respectively in the vertical planes of said stringers, rocker bearings mounted at opposite sides of the machine upon said base and arranged in opposed pairs, connecting shafts operatively relating 30 said pairs and links connecting said rocker bearing shafts for synchronous actuation.

35. In a drying machine, in combination, a platen supporting frame having upper and lower longitudinal members, a second platen 35 supporting frame having upper and lower longitudinal members arranged in the plane of said first mentioned members and supported for longitudinal movement thereon, platen supporting posts carried by said members, platens carried by said posts, a supporting base for said frames disposed below the plane of said members, rocker bearings supported on said base having supporting connections with said first mentioned frame, 40 rockers in said bearings provided with crank arms disposed at the inner sides of said base and operating links connecting said crank arms. .

36. In a drying machine, in combination, 50 a platen supporting frame having upper and lower longitudinal members, a second platen supporting frame having upper and lower longitudinal members arranged in the planes of said first mentioned members and supported for longitudinal movement thereon,

platens supporting posts carried by said members, platens carried by said posts, a supporting base for said frames arranged in the planes of said members, rocker bearings supported on said base having supporting connections with said first mentioned frame, 60 rockers in said bearings having crank arms disposed at the inner sides of said base, operating links connecting said crank arms disposed at either side of the machine, and 65 power connections for actuating said links.

37. In a drying machine, in combination, a base, relatively movable frames supported on said base provided with vertically reciprocating members, platens carried by said members, and means for supplying heating medium to said platens, said means comprising separate supplying and draining headers carried respectively by said relatively movable frames, and flexible piping leading individually from said headers to each platen. 70

38. In a drying machine, in combination, a base, relatively movable frames supported on said base and having vertically reciprocating members, platens carried by said members, 80 and means for supplying heating medium to said platens, said means comprising upper and lower headers carried respectively by said relatively movable frames, said upper headers being adapted to supply live steam, 85 said lower headers serving to drain off condensate, and flexible piping leading from said headers to each platen, said piping being provided with individual flow controlling means. 90

39. In a drying machine, in combination, a base, relatively movable frames carried by said base, each having upper and lower members reciprocable toward and from the other, platens arranged in groups to form batteries 95 supported by said members, driving means in said base for reciprocating said members and effecting relative movement of said frames, and means for supplying said batteries with a heating medium, said means comprising upper supply headers carried respectively by said relatively movable frames, and lower drain headers carried respectively by said frames, and flexible pipe connections leading from said headers to each individual platen, 100 the pipe connections leading to the platens in the same battery being arranged in groups. 105

In testimony where we affix our signatures.
